GYRATORY SCREEN

Francois Jacques Berry, Lille, France

Application September 8, 1945, Serial No. 615,183
In France May 14, 1943

2 Claims. (Cl. 209—326)

1

It has already been suggested, in the construction of sieves adapted for the granulometric or densimetric sorting out of products in a divided state, to control the motion of the sieve by means of an eccentric, the strap of which is fast with the movable part, the latter being suspended at its ends by means of springs making it possible to cause all the points of the sieve to follow parallel trajectories. In this case, the trajectory of each point is a circumference of a small amplitude.

The present invention has more particularly for its object to provide an improvement in or relating to the control of the movements of such sieves in order to cause each point of the sieve to follow an elliptic trajectory having a selected amplitude and a selected slope so as to obtain, for the particles to be treated on the sieve, advancing movements adapted to ensure the sorting out of said particles according to their dimensions or their densities under better conditions.

For this purpose, according to the invention, the control device for the movements of the movable frame of the sieve comprises, preferably on each side of the latter and close by the centre of gravity of the movable unit, two eccentrics fast with a common driving shaft and the centres of which are situated in one and the same diametral plane of said shaft, said eccentrics being connected with the frame of the sieve by two connecting rods keyed at 90° from one another. The rotation of the driving shaft then determines for each point of the sieve a displacement according to an ellipse the two half-axes of which correspond respectively to the offsettings of the eccentrics. According to the vertical or slanting position given to the connecting-rod of the eccentric having the greatest offsetting, for instance, the obtained trajectory is an ellipse with a vertical or slanting major axis.

According to another characteristic feature of the invention the device for the suspension of the sieve comprises four links arranged near the four angles of the movable frame and formed each of two telescopically jointed members kept apart by compressed springs, each of said links being articulated at its ends, on one hand, on the fixed frame of the apparatus and, on the other hand, on the movable frame of the sieve. A simple and advantageous kind of articulation of the supporting links may consist in providing the sliding pieces forming each of the latter with heads having a cylindrical or spherical surface and leaning respectively against resting faces fast with the fixed frame and the movable frame and provided

2

with transverse grooves engaging corresponding projections provided on said resting faces.

The improved sieves according to the invention may eventually be placed, in the known manner, in a liquid or gaseous medium (as in the case of a pneumatic purification) to which a continuous or discontinuous flowing movement may be imparted or not.

A form of execution of the arrangements which 10 form the subject-matter of the invention is shown by way of non-limitative example in the appended drawing, in which:

Fig. 1 is a diagrammatical elevational view of 15 the movable unit of the sieve with its elastic suspension.

Fig. 2 is a vertical axial sectional view, on a larger scale, of one of the lateral control devices for the movements of the sieve, taken on the line II—II of Figure 3.

Fig. 3 is a sectional view taken through line 20 III—III of Fig. 2.

Fig. 4 shows the elliptic trajectory described in 25 this case by each point of the sieve.

Fig. 5 is a vertical view of one of the links for 30 the suspension of the sieve, and

Fig. 6 is a similar view of a modification.

In Fig. 1, 1 shows the shifting screen of the sieve which is held fast between two longitudinal members 2 resting at their ends on two pairs of spring supports or links 3. The control device for the movement of the sieve, which is shown in A, is placed in the middle part near the centre of gravity of the movable unit.

Said control device comprises here (Figs. 2 and 35 3) a housing 4 secured on each member 2 of the sieve. Through both housings 4 extends a driving shaft 5 carried by two fixed bearings 6 arranged on both sides of the sieve and carrying, at one of its ends, a driving member (pulley, coupling sleeve 40 or the like), not shown. Within each housing the shaft 5 comprises two parts 7a, 7b thrown off centre and the centres 0₁ 0₂ of which are situated in one and the same diametral plane and the offsettings 00₁ and 00₂ of which correspond respectively to the lengths of the half-axes of the ellipse 45 along which the different points of the sieve are to travel. The two eccentrics 1a, 1b are connected with the two cheeks of the housing 4 by links 8a, 8b, keyed at 90° from each other and by axes 9a, 9b. Therefore, the rotation of the eccentric 1a determines displacements of the housing 4 and, 50 accordingly, of the whole sieve according to a to-and-fro movement the amplitude of which is equal to its stroke and according to the direction 55 0—9a, while the rotation of the eccentric 1b deter-

mines another to-and-fro movement the amplitude of which is equal to the stroke of said eccentric and according to the direction 0—9b. Through combining with each other, both said orthogonal movements impart to the sieve a resulting elliptic movement.

In the example shown, the foot of the connecting rod 8a being fixed on the vertical line of the axis of the shaft 5, the trajectory of each point of the sieve is an ellipse the major axis of which is vertical, as shown in Fig. 4 at a—c. Through placing the foot of the connecting rod on a slanting radius issuing from centre 0 one would obtain an elliptic trajectory the great axis of which would be slanting, as shown in broken lines in Fig. 4.

The spring links 3 through which the longitudinal members of the sieve are supported at their ends and which makes it possible for all the points of the sieve to describe the same movement may be constituted respectively, as shown in Fig. 5, by two pieces 10, 11 sliding in each other and kept apart from each other by a spring 12. Said pieces are provided with heads 10a, 10b having a cylindrical surface and through which they lean, on one hand, against a resting 13 integral with the fixed frame of the apparatus and, on the other hand, against a face 14 integral with the corresponding member 2. In order to avoid any displacement of the spring links on their supports 13—14 their heads are provided with transversal grooves 10b, 11b having a suitable profile and engaging projections 13a, 14a having a corresponding profile and provided on the resting faces 13 and 14. Under these conditions the horizontal displacements of the sieve cause the links 10—11 to turn on the projections 13a, 13b; the vertical displacements are effected through a compression or an extension of the links. Since the springs and the links have the same characteristics, the displacements of the sieve are the same in all points.

The cylindrical or spherical rolling heads 10a, 11a might be substituted by sockets such as 15a, 15b (Fig. 6) which would be engaged by axes held fast respectively on the fixed part and on the movable part of the apparatus.

In order to make it possible to change the setting of the connecting rods 8a and 8b with respect to the frame of the sieve for modifying at will the slope of the major axis of the ellipse described by the elements of the sieve with respect to the horizontal line, the housing 4 might be mounted so that it could be possible to displace it angularly around the axis of the shaft 5, for instance by means of an adjusting mechanism comprising a worm engaging a helicoidal wheel fast with the housing.

An arrangement such as described above is shown in Figures 2 and 3. The housing 4 is attached to the frame 2 by means of headed studs a₁, b₁, c₁, and d₁, which ride in the arcuate slots a₂, b₂, c₂, and d₂. The frame 2 is provided with slots 19a and 19b in which ride the axles 9a and 9b. The housing carries a toothed sector 16 cooperating with a worm 17 mounted in bearings 18a and 18b. The position of the links 8a and 8b may be adjusted by rotating the worm 17 so as to vary

the position of the major axis of the elliptical path of the sieve.

What I claim is:

1. In a sieve for sorting solid materials comprising a movable frame spring mounted at its ends, a driving shaft for said frame, two eccentrics fixed on said driving shaft near the center of gravity of said frame, the centers of said eccentrics being located in the same diametral plane of said shaft, a connecting rod fixed to each of said eccentrics, a housing for said connecting rods rotatably mounted on said frame for rotary movement around the axis of the shaft, and said connecting rods at their ends being pivoted to said housing, at an angle of 90° to each other, and means connected between the housing and the frame for adjusting the housing about the axis of the shaft, whereby angular displacement of said housing will vary the major axis of the elliptical path of said sieve.

2. In a sieve for sorting solid materials comprising a movable frame spring mounted at its ends, a driving shaft for said frame, two eccentrics fixed on said driving shaft near the center of gravity of said frame, the centers of said eccentrics being located in the same diametral plane of said shaft, a connecting rod fixed to each of said eccentrics, a housing for said connecting rods rotatably mounted on said frame for rotary movement around the axis of the shaft, and said connecting rods at their ends being pivoted to said housing at an angle of 90° to each other, and means connected between the housing and the frame for adjusting the housing about the axis of the shaft, said housing being provided with a toothed sector and said frame carrying a worm operatively engaging said sector whereby rotation of said worm produces angular displacement of said housing to vary the major axis of the elliptical path of said sieve.
